(57) **CLAIM**

The ornamental design for a doll for holding a multiplicity of remote control units, as shown and described.

DESCRIPTION

FIG. 1 is a front perspective view showing my new invention for a doll for holding a multiplicity of remote controls; FIG. 2 is a rear perspective view thereof, shown at a reduced scale; and,

FIG. 3 is a rear perspective view thereof, taken from another direction and on a reduced scale from FIG. 2.
